Inventor:

George J. Dickinson

UNITED STATES PATENT OFFICE.

GEORGE J. DICKINSON, OF NEW HAVEN, CONNECTICUT.

BLOTTER.

1,277,703.

Specification of Letters Patent. Patented Sept. 3, 1918.

Application filed August 23, 1917. Serial No. 187,914.

To all whom it may concern:

Be it known that I, GEORGE J. DICKINSON, a citizen of the United States, residing at New Haven, in the county of New Haven and State of Connecticut, have invented a new and useful Improvement in Blotters; and I do hereby declare the following, when taken in connection with the accompanying drawings and the characters of reference 5 marked thereon, to be a full, clear, and exact description of the same, and which said drawings constitute part of this application, and represent, in—

Figure 1 a perspective view of my improved blotter indicated as applied to the wrist of a penman and in position for blotting.

Fig. 2 a perspective view of the blotter detached, showing absorbent material separated from the strap.

This invention relates to an improvement in blotters, and particularly to blotters adapted to be connected with the wrist, the object of the invention being to provide a simple device to which pieces of blotting paper or other long and narrow absorbent material may be readily attached and detached, and which is conveniently secured upon the wrist in convenient position for the use by accountants and others working with pen and ink which require the frequent use of a blotter, and the invention consists in the construction hereinafter described and particularly recited in the 30 claim.

In carrying out my invention I employ a strap 3 of flexible material, such, for instance, as leather, the ends 4 and 5 of the strap being narrower than the central por-

tion, and one end being provided with a 40 buckle 6 and the other end with perforations 7, whereby the ends of the straps may be connected together around the wrist. It is obvious, however, that any of the well known means for connecting the ends of 45 the strap may be employed. At the ends of the central portion of the strap I form slots 8 and 9 to receive tongues 10 and 11 formed at the opposite ends of a strip 12 of blotting paper or other suitable absorbent 50 material, the central portion of which corresponds to the central portion of the strap 3 so as to practically cover it. The tongues 10 and 11 of blotting material are passed through the slots 8 and 9 so that the absorbent material covers the outer face of the central portion of the strap and the tongues extend along the inner surfaces of the ends of the strap. The device is then secured to the wrist and is therefore in constant position for use, leaving the fingers of the penman free. From time to time, as required, the absorbent strip may be readily removed and replaced by a fresh one.

I claim:—

A blotter comprising a strap having a wide, central portion and narrow ends, means for connecting the said ends together, said strap formed with slots at the ends of the central portion, combined with a strip 70 of absorbent material the central portion of which corresponds substantially to the central portion of the strap and formed at each end with a long narrow tongue adapted to be inserted through the slots in the strap 75 and extending along the inner surfaces thereof.

GEORGE J. DICKINSON.
